UNITED STATES PATENT OFFICE.

LAWRENCE STOCKMAN, OF PHILADELPHIA, PENNSYLVANIA.

TABLE.

SPECIFICATION forming part of Letters Patent No. 407,908, dated July 30, 1889.

Application filed September 1, 1888. Serial No. 284,376. (No model.)

To all whom it may concern:

Be it known that I, LAWRENCE STOCKMAN, of Philadelphia, in the county of Philadelphia and State of Pennsylvania, have invented 5 certain new and useful Improvements in Tables; and I do hereby declare the following to be a full, clear, and exact description of the invention, such as will enable others skilled in the art to which it appertains to make and 10 use the same.

My invention relates to improvements in tables; and it consists of the peculiar construction and arrangement of parts, as will be hereinafter fully described and claimed.

15 My invention contemplates an improved table of simple and cheap construction, having two of the four legs thereof fixed or stationary with the frame of the table and the other two legs adjustable at an angle to the 20 said frame, on opposite sides thereof, to form supports for two drop-leaves, whereby the area of the table-top can be varied without the use of additional legs or other supporting devices. I am thus enabled to provide a four- 25 legged table which is capable of fulfilling all the functions of the ordinary extension-table with six legs and to dispense with a knuckle-joint, and the two adjustable legs are adapted to lie within notches in the frame of the ta- 30 ble, and thus be compactly folded out of the way and assist in supporting the table when it is desired to fold the drop-leaves.

In the accompanying drawings, Figure 1 is 35 a plan view of a table-frame with the table-top removed and one of the adjustable legs swung out at an angle to the frame. Fig. 2 is a side view showing one of the adjustable legs partly folded within the slot and notch in one side of the frame; and Fig. 3 is a vertical sectional view on the line $x-x$ of Fig. 1, with the table-top in place, one of the leaves being folded and the other raised.

Referring to the drawings, in which like 45 letters of reference denote corresponding parts in all the figures, A designates the frame of the table, which comprises the parallel side bars $a a$ and end bars $a' a'$, which are firmly united together. At diagonally-opposite corners of the frame are secured stationary legs 50 B B', and at the other corners of said frame are made notches or recesses $c c'$, of sufficient

size to adapt the upper extremities of the adjustable legs C C' to fit snugly therein and lie substantially flush with the outer exposed faces of the bars $a a'$ of said frame, as shown 55 in Fig. 1. It will be noticed that one of these recesses or notches is made in one end of each side bar a of the frame, and each side bar is further provided with a longitudinal slot c^2 , which extends from a point at or near the 60 middle of the bar and opens at one end into the notch or recess, as indicated in Fig. 2.

To each of the adjustable legs C C' of the table is secured or fixed a tie-bar D and D', respectively, and the free or unconfined end of 65 each tie-bar is pivoted on a vertical pin or shaft d in the inner end of one of the slots c^2 . These tie-bars are of sufficient width to fit snugly in the longitudinal slots c^2 in the frame A, and when the adjustable legs C C' are moved into 70 the recesses or notches in diagonally-opposite corners of the frame A said tie-bars D D' fit in the slots flush with the exposed faces of the bars $a a'$, as indicated in Figs. 1 and 3.

E is the top, which is securely fixed to the 75 frame A of the table in any preferable manner, and E' E² are the hinged drop-leaves, one leaf being arranged on one side of the top and the other on the opposite side thereof. (See Fig. 3.)

The operation of my invention is obvious 80 from the foregoing description, taken in connection with the drawings.

When it is desired to unfold the table, one of the leaves E' or E² is raised to a horizontal 85 position, and the corresponding leg C or C' is drawn outwardly away from the frame A and adjusted beneath said raised leaf in the position indicated in Figs. 1 and 3 to prevent the free end of the leaf from dropping and to 90 support the table. It is obvious that to fold the leaf it is only necessary to push the leg and its tie-bar into the notch and slot, respectively, of the frame, in which said leg and bar fit flush, so as to be compactly stored out 95 of the way, when the leaf can be dropped.

Either leaf and its supporting-leg can be 100 adjusted or folded independently of the other leaf and leg; or, if it is desired to use the entire table-top, both leaves can be raised.

The adjustable legs assist in supporting the table, whether they are folded within the

frame A or withdrawn therefrom to support the leaves. By the use of these adjustable legs at diagonally opposite corners of the frame A, I am enabled to provide a table having but four legs which fulfills the functions of a six-legged table and without the use of a knuckle-joint, thereby materially cheapening the manufacture of the table and preserving the external contour of the ordinary table.

10 Having thus fully described my invention, what I claim as new, and desire to secure by Letters Patent, is—

In a table, the combination of a frame having the fixed legs B B' at diagonally-opposite corners and the recesses c c', formed therein at the remaining corners thereof, each side bar of said frame having a longitudinal

slot extending from a point near the middle of said bar to one of said recesses, the tie-bars each pivoted at one end in one of said slots, 20 at the inner end thereof, and adapted to be folded within the same to lie flush with the side bars of the frame, the adjustable legs fixed to the free unconfined ends of said tie-bars and adapted to fit in the recesses c c' 25 when said bars are folded in the slots, and a top fixed to the frame and having the hinged leaves, substantially as described.

In testimony whereof I affix my signature in presence of two witnesses.

LAWRENCE STOCKMAN.
